UNITED STATES PATENT OFFICE.

FRANZ KŇOUREK, OF MIES, AUSTRIA-HUNGARY.

TURBINE.

1,085,088.

Specification of Letters Patent.

Patented Jan. 20, 1914.

Application filed November 6, 1913. Serial No. 799,537.

To all whom it may concern:

Be it known that I, FRANZ KŇOUREK, a subject of the Emperor of Austria-Hungary, and resident of Mies, Bohemia, Austria-Hungary, have invented a new and Improved Turbine, of which the following is a clear, full, and exact description.

This invention relates to improvements in turbine motors, the primary object of the improvement being to provide means whereby the water, steam or other fluid employed will traverse in substantially a plurality of circular channels to cause the rotor and its casing to revolve.

15 A further object of the invention is to provide means for controlling the flow of the motive fluid so as to cause the latter to pass through the channels in any number of plates forming the rotor and to provide 20 means for reversing the rotor, whereby to provide convenient and effective means for controlling the motor.

Another object of the present invention is to provide improvements in the means employed in the channels to produce the most 25 effective force of the fluid.

The invention also comprehends improvements in the details of construction and arrangement of parts which will be hereinafter 30 described and particularly pointed out in the claims.

In the accompanying drawings: Figure 1 is a longitudinal central section of my improved motor, the reversing valves being in 35 full lines; Fig. 2 is a transverse section on the line A—B of Fig. 1; Fig. 3 is a detail section on the line C—D of Fig. 2; Fig. 4 is a detail section on the line E—F of Fig. 2; Fig. 5 is an end elevation of the central portion 40 of the motor; Fig. 6 is a detail cross section on the line K—L of Fig. 7; Fig. 7 is a detail section on the line G—H of Fig. 6; Fig. 8 is a detail section on the line P—Q of Fig. 9; Fig. 9 is a detail section on the line 45 M—N of Fig. 8; Fig. 10 is a detail perspective view of one of the water deflectors; Fig. 11 is a detail longitudinal section of a slightly modified form of the invention; and Fig. 12 is a detail section of the end of one 50 of the screw stems and its gear, for operating the controlling valves.

1 indicates a central shaft and on this shaft is keyed a plurality of circular plates, seven being shown in the drawing, same 55 being indicated by numerals 2, 3, 4, 5, 6, 7

and 8. Plate 2 forms the end of a casing and is of greater diameter than the companion plates. The casing is formed, in addition to the end plate, by a plurality of rings 18, and a head 9, the rings being spaced from the peripheries of the plates to form an annular passage 26', while the head 9 is spaced from plate 8 to form a fluid chamber 19, with which passage 26' communicates. End plate 2 is formed with a central tubular extension 10, through which the fluid flows to the rotor, while head 9 is formed with a central tubular extension 11, through which the fluid flows from the rotor. End plates 2 and 3 are each provided on one surface with a plurality of concentric ribs 12, 13, 14, 15, 16 and 17, and the other plates have similar ribs, but extending from both flat surfaces of said plates. These ribs are spaced apart and when the plates are assembled in position on the shaft, form a plurality of concentric channels, as clearly shown in Fig. 2. The ribs are mutilated to receive reversing valves 26, operating in seats 27, formed in the faces of adjacent plates. The reversing 20 valves are exactly alike, and but one will be described. Valve 26 comprises a tapered plug and a stem 38, the latter operating in a bearing on the casing. In the plug portion of the valve are inclined ports 32, 33, 34, 35, 36 and 37, the inclination of said ports being such as to form communication between successive concentric channels. The inner end port 32 is in constant communication with the space in the hub of the plate, inside the 25 rib 12, while port 37 is so formed as to be in constant communication with the passage 26'. By turning the reversing valves half a revolution from the position shown in Fig. 2, the course of the fluid will be reversed, 30 hence the motor will be reversed.

To the stems of each reversing valve is secured a pinion 39, the pinions being of such diameter as to mesh, as indicated in Fig. 1. Mounted to slide on the periphery 35 of the casing is a ring provided with teeth 40, which mesh with the end pinion 39. The ring 40 may be operated in any suitable manner to change the position of the valves.

Extending from rings on the periphery of the casing are two spaced apart lugs 42 and 43, and extending from the ring 40 is a lug 41. Now if the ring 40 be held and the casing is rotated, obviously the lug 42 will contact with lug 41 and move the latter up to 40

the next lug 43, and vice versa. This movement is timed to rotate the reversing valves one-half revolution.

Each of plates 2, 3, 4, 5, 6, 7 and 8 is formed with a series of horizontal alined openings 21, 22 and 24, located inside the plane of the inner ribs 12. The openings in the plates are in alinement, and communicate with chambers 23. Extending through the respective openings are screws 25, which stems fit in bearings formed in the end plates 2 and 8. On the screws are threaded valves 24^a formed with extensions 24^b, which fit in grooves to form guides.

On the end of each screw 25 is a pinion 44, and meshing with said pinions are inner and outer toothed rings 46 and 45, which operate in guides 45^a. The toothed rings rotate with the casing, hence to rotate the screws; either means may be provided to hold one or the other of the rings, which of course will rotate the pinions.

The valves 24^a are for the purpose of controlling the fluid, so that as many of the channels in the plates may receive the fluid as may be selected to obtain the desired power and speed. Obviously by rotating the screws 25, the valves 24^a are moved in the alined openings, so that the fluid can be cut off from as many plates in the series as might be selected. For instance, as shown in Fig. 1 only, the channels formed between the plates 2, 3 and 4 will receive the fluid, for obviously, as the openings in the next plate are closed, the fluid is prevented from going farther.

In order to add to the efficiency of the fluid passing through the channels formed between the ribs on the plates I insert baffles 47, shown in Figs. 6, 7 and 10. The central baffles comprise two spaced apart plates 47', connected by a web 52, from the ends of which extend legs 48. Each plate 47' is bulged at the center, and inclined toward the ends of the adjacent plate, but the opposite ends of both said plates are slightly spaced to form an opening. The outermost baffles are similar to those in the middle of the channels, except that but a single plate is employed, and the ends of this one are slightly spaced from the ribs, as clearly shown in Fig. 7. The legs 48 fit in grooves 50 formed in the walls of the channels, which afford convenient means for holding the baffles in position. The baffles shown in Figs. 8, and 9 are disposed at right angles to those shown in Figs. 6, 7 and 10, the legs 48' fitting in grooves 50.

In the form of the invention shown in Fig. 11, the circular plates 2', 3', 4' and 5' are formed on their flat surfaces with grooves, in which rings 16' fit to form the channels. The outer rings 17' which form the outer walls of the rotor are formed with grooves to receive the edges of the plates.

In operation the fluid passes through the tubular extension 10, and into the chamber 23, from thence it passes through the port 32, and around the first channel, and from the latter through port 33, and so on until port 37 is reached. From port 37 the fluid passes into the passage 26', thence to chamber 19 and out the tubular extension 11. In passing through the channels, the fluid is caused to take a circuitous path, due to the disposition of the baffles 47. The pointed ends of the baffles are disposed parallel or perpendicular to the axis of the motor, thus the inrushing fluid passes through the open ends of the baffles and acts against the middle wall thereof and serves to impart motion to the rotor. I find that I obtain a higher degree of efficiency by making the baffles hollow, as the pressure of the fluid acting from the inside is concentrated. Furthermore, because of the shape and disposition of the baffles, the fluid acts on both halves of each baffle producing inside pressure in the front half and inside dilatation in the rear half of the baffles. To reverse the motor, the ring 40 is operated as previously described, and through the pinions 39, the valves are turned half revolution, and because of the construction of the ports the fluid will be caused to flow in the opposite direction in the channels. When the fluid enters the chamber 23, and if the controlling valves 24^a are positioned back in the seats in the end plate 8, said fluid will flow through the openings 21, 22 and 24, to the next chamber 23, and so on throughout the series of plates. The result is, the fluid will flow through the channels in all the plates. Now if it be desired to reduce the power of the motor, the screws 25 are operated as previously described, and the valves 24 are advanced; for instance, to the position shown in Fig. 1, hence the fluid cannot flow through the openings 21, 22 and 24, of plates 5, 7 and 6.

What I claim is:—

1. In a motor of the character described, the combination of a shaft, a plurality of plates mounted on the shafts, said plates having concentric ribs which form channels, the inner ribs forming a central chamber around the shaft, a casing surrounding and spaced from the plates to form a passage, the plates having means to direct fluid from the central chambers through to one channel, and thence to the next succeeding channel, the outermost channel between adjacent plates having an outlet to the passage, baffles in the channels, means for introducing fluid to the chambers, means for controlling the fluid passing to the chambers, the casing having an exit for the fluid which has passed through the channels.

2. In a motor of the class described, the combination of a shaft, a rotor mounted on

the shaft, said rotor having sets of concentric channels and a central chamber for each set of channels, the rotor having openings to provide communication between all of the 5 chambers, a reversing valve operating in each set of channels, each of said valves having ports to form a continuous passage from a chamber and a set of channels to the periphery of the rotor, means for simultaneously operating the reversing valves, valves in the openings communicating with the chambers, means for controlling the valves, a casing surrounding and spaced from the rotor, inlet flues communicating with the 10 end chamber and an outlet flue communicating with the casing.

3. In a motor of the class described, the combination of a shaft, a plurality of plates mounted on the shaft, said plates having 20 ribs to form a central chamber and a plurality of concentric channels, means to form a continuous passage from each central chamber through the channels of adjacent plates to the periphery of said plates, each 25 chamber having an opening to form communication with the adjacent chamber, threaded rods extending through the said openings, valves mounted on the threaded rods, means for simultaneously rotating the 30 threaded rods to operate the valves to open or close the respective chambers, a casing surrounding and spaced from the plates, an inlet flue communicating with one of the 35 end chambers, and an exit flue communicating with the casing.

4. In a motor of the class described, the combination of a rotor formed with a series 40 of sets of concentric channels, and a central chamber for each set of channels, the adjacent channels in each set communicating, the innermost channel of each set communi-

cating with a chamber, and the outermost channel opening out at the periphery of the rotor, a plurality of hollow baffles in each channel, each baffle comprising hollow 45 bulging tapering sides, the ends being open to form inlet openings, and a partition between the plates, a casing surrounding and spaced from the rotor, the outermost channels communicating with the space between 50 the rotor and the casing, an inlet flue communicating with the first chamber, the chambers having openings to form communication therebetween, valves operating in the latter openings to control the flow of 55 fluid to the chambers, and an exit flue in the casing.

5. In a motor of the character described, the combination of a rotor provided with a series of sets of concentric channels and a central chamber for each set of channels, the chambers having outer communicating openings, a casing surrounding and spaced from the rotor, a valve for each set of channels, said valves extending through the casing, each valve having a plurality of inclined ports to form communication between a chamber and a set of concentric channels and the periphery of the rotor, a pinion on each valve, means on the casing for simultaneously operating all the pinions to rotate the valves, controlling valves operating in the openings in the chambers, means outside the casing for simultaneously operating the controlling valves, an inlet flue for introducing fluid to the chambers, and an outlet flue in the casing to carry off the fluid. 70 75
